Patented Feb. 13, 1917.

UNITED STATES PATENT OFFICE.

RALPH P. TUTTLE, OF NEW YORK, N. Y.

SEMAPHORE-SIGNAL DEVICE.

1,216,020.

Specification of Letters Patent. Patented Feb. 13, 1917.

Application filed April 26, 1913. Serial No. 763,705.

To all whom it may concern:

Be it known that I, RALPH P. TUTTLE, a citizen of the United States, residing in the borough of Manhattan, city, county, and 5 State of New York, have invented certain new and useful Improvements in Semaphore-Signal Devices, of which the following is a specification.

My invention relates to semaphore signal devices, and particularly to semaphore signal devices used in connection with railway signal mechanisms. An object of my invention is to provide for a light weight blade which can be easily attached and detached 10 to the semaphore casting. I will describe a semaphore signal device embodying my invention, together with a modification thereof, each embodying my invention, and then point out the novel features thereof in 15 20 claims.

In the accompanying drawings, Figure 1 is a side elevation of a signal device embodying my invention. Fig. 2 is a top plan view of the device of Fig. 1. Fig. 3 is a vertical sectional view taken on the line 3—3 of Fig. 1, but drawn to a larger scale. Figs. 25 4 and 5 are detail views, the latter being a sectional view taken on the line 5—5 of Fig. 1. Fig. 6 is a view similar to Fig. 1, 30 but showing a modification. Fig. 7 is a top plan view of the device shown in Fig. 6. Fig. 8 is a vertical sectional view taken on the line 8—8 of Fig. 6, but drawn to a larger scale.

Similar letters of reference designate corresponding parts in all of the figures.

A designates what is termed in the art as a "spectacle casting," which, as usual, carries colored glass disks (not shown) and is provided with what is known as a blade grip α . The casting A, as usual, is mounted on a shaft which is operated to move the casting, and with it, the colored lenses and blade, against the usual bias of the casting and 45 blade. The form of invention shown in the drawings is adapted for use in connection with semaphore signal devices, the indications of which are given in the upper quadrant, though my invention is equally applicable to signal devices which indicate in 50 the lower quadrant.

B designates a supporting piece, preferably of metal, and here shown as being T shape in cross-section, which is suitably rigidly connected with the blade grip of

the casting A. The piece B is also adapted to add strength to the blade, which is supported therefrom. The piece B may be rigidly connected with the casting by any desired means. It is shown as being connected 60 with the back of the blade grip, and in Fig. 1 the piece B is retained in position between two pairs of opposed plates b , b , which are held by bolts b^2 and nuts b^3 . This is best shown in Fig. 3. In Fig. 6, the piece B is 65 rigidly connected with the back of the blade grip by means of a U bolt b^4 , the ends of which are threaded to receive nuts b^5 , and by a bolt b^6 and nut b^7 which passes through the piece B and the blade grip. 70

C designates a signal blade which is adapted to be supported from the piece B. This is accomplished by means of a strap c (here shown as being in the form of a pocket) secured to the blade into which the 75 end portion of the piece B extends (see Fig. 5) and clips c' , c' also secured to the blade which engage with a cross piece b^8 (see Figs. 2 and 4) secured to the piece B. The blade may also be connected with the spectacle A, (if necessary) by any desired means. As shown in Fig. 1, these means comprise the ends of the bolts b^2 which extend through openings in the blade C and nuts b^{10} , suitable fiber or other washers b^{11} are 80 employed on both sides of the openings in the blade. In Figs. 6, 7, and 8, the means are the end of the bolt b^6 which extends through an opening in the blade C, and a nut b^{12} , washers b^{13} are also employed on 85 both sides of the opening in the blade. 90

The blade C may be of wood or metal. The blade shown in the drawings is of metal, with the longitudinal edge portions bent at an angle, in order that the blade shall be 95 stiffened, and to prevent the edges of the blade warping during heating in case the blade is enameled.

In the form of invention shown in Figs 1 and 2 the blade is slightly sprung when it 100 is placed on the supporting pieces, whereas in the form of invention shown in Figs. 6 and 7, the supporting piece B is offset at that portion adjacent to the blade grip, so that there is no need of springing the blade 105 when it is placed in position on the supporting piece.

All that is necessary to place the blade in position on the supporting piece is to pass the strap c over the end of the supporting 110

piece B until the clips c' engage with the cross-piece b⁸. The blade is then held in position by means of the bolt or bolts passing through the openings.

5 Having thus described my invention, what I claim as new is:

1. A railway signal device, having in combination, a spectacle casting, a blade, a piece B from which said blade is slidably supported, and independent means for connecting said supporting piece with a spectacle casting.

10 2. A railway signal device, having in combination a spectacle casting, a blade, a piece B from which said blade is slidably supported, means for connecting said supporting piece with said spectacle casting, and independent means for connecting the blade with said spectacle casting.

15 3. In a railway signal device, the combination of a spectacle casting, a supporting piece carried thereby, a blade, and means for removably supporting the blade from said piece, said means comprising a part carried by the blade and engaging the end portion 20 of said piece, and another part also carried

by the blade and engaging with a part carried by the supporting piece.

4. In a railway signal device, the combination of a spectacle casting, a supporting piece carried thereby, a blade, and means for removably supporting the blade from said piece, said means comprising a part carried by the blade and engaging the end portion 30 of said piece, and two other parts also carried by the blade and engaging with a part carried by the supporting piece.

35 5. A railway signal device comprising a spectacle, a supporting piece secured thereto, a substantially flat signal blade, a strap carried by the blade and engaging the end portion of the supporting piece and clips also secured to the blade and engaging with the supporting piece whereby the blade is 40 removably supported from the said piece.

45 In testimony whereof, I have signed my name to this specification, in the presence of two subscribed witnesses.

RALPH P. TUTTLE.
